UPRIGHT VACUUM CLEANER OR SIMILAR ARTICLE

Bertrand N. Trombley, Birmingham, Mich., assignor to Kingston Products Corporation, Kokomo, Ind., a corporation of Indiana

Filed Nov. 19, 1962, Ser. No. 72,545

Term of patent 3½ years

(Cl. D9—2)

FIGURE 1 is a side elevational view of an upright vacuum cleaner, or similar article embodying my new design the opposite side being substantially the same.

The dominant features of my design reside in the portions shown in full lines.

I claim:

The ornamental design for an upright vacuum cleaner, or similar article, substantially as shown and described.
